UNITED STATES PATENT OFFICE.

EDWIN HANSALPAKAR, OF BROCKTON, MASSACHUSETTS, ASSIGNOR TO BROCKTON HEEL COMPANY, INC., OF CAMPOLLO, MASSACHUSETTS, A CORPORATION OF MASSACHUSETTS.

MACHINE FOR BUILDING RANDED HEELS.

Application filed June 12, 1925. Serial No. 38,665.

This invention relates to machines of the general type illustrated in my prior Patent No. 1,534,313, dated April 21, 1925, such machines being provided with a mold in which lifts are placed to form heels, and with a presser organized to operate to force successive assemblages of adhesively coated lifts and intermediate separators, through such mold and into a chute wherein such assemblages of lifts are allowed to remain until the adhesive has sufficiently dried.

The purpose of this invention is to enable heels provided with rands to be built according to the method carried out with the aid of such machines, and to provide machines of this type with means enabling rands to be applied and united to the heel bodies at the same time that the lifts are assembled and pressed together to form such heel bodies, and to provide also means for trimming the excess stock from the ends of the rand strips at the same time that the lifts and rands are put under compressing pressure. Further objects are concerned with improvements in the structural features of machines of this type or character, as will appear from the following detailed description of the preferred form of my improved machine. The invention consists in means for accomplishing the above named objects, in combination with the essential structural and operating parts of a machine of the general type referred to, and in the method of producing heels which is performed or carried out with the aid of such means. It further embraces the novel structural and operative characteristics, in detail and in combination, embodied in the machine herein illustrated and in equivalent machines and structures.

Referring to the drawings provided herewith,—

Fig. 1 is a side elevation of a preferred form of heel building machine containing and embodying the mechanical improvements involved in this invention.

Fig. 2 is a sectional detail view of the driving pulley and clutch, with associated control means, by which the movements of the machine are effected;

Fig. 3 is a front elevation of the machine shown in Fig. 1;

Fig. 4 is a cross section taken on the line 4—4 of Fig. 1;

Fig. 5 is a fragmentary detail of the eccentric and eccentric rod by which the presser element of the machine is actuated;

Fig. 6 is a plan view of the entire machine;

Figs. 7 and 8 are detail views showing the latch for the control arm or treadle in different positions;

Fig. 9 is a fragmentary perspective view showing a part of the movable presser carrying head;

Fig. 10 is a perspective view of the presser element and of its cutter-holding clamp detached therefrom;

Fig. 11 is a perspective view of the mold in which the lifts and rand are assembled and confined in the operation of building a heel;

Fig. 12 is a perspective view of a heel provided with a rand and built according to the method and by the aid of a machine embodying this invention.

Like reference characters designate the same parts wherever they occur in all the figures.

The frame of the machine comprises a base 80 15, and a column 16. On the column is a table 17 containing a mold or die 18, (shown in detail in Fig. 11,) in which collections of lifts, alternating with separators, are placed to form heels. Said mold or die is preferably made in two parts, 18^a and 18^b, which, being placed together, as shown in Fig. 11, provide a passageway or cavity conforming in cross section to the shape and the dimensions of the heels to be made. Said members 90 of the mold have flanges 19, which rest on the table, and preferably lie in a shallow recess in the upper side thereof, while the main portions of the mold extend through an opening in the table. Lugs 20—20 (Fig. 95 6), attached to the top of the table at each side of the mold, overlap said flanges 19 and prevent lifting of the mold, while a transverse bar 21 secured across the front of the table closes the flange-receiving cavity on 100

that side. Key pieces 22—22, fragments of which are shown detached in Fig. 11, when placed in matching keyways 23—23 in the parts of the mold, align said parts. Blocks 5 24—24 are secured to the upper end of the mold at the rim of the passageway therein, and have beveled interior surfaces forming a flaring mouth to the mold cavity, which facilitates placement by the operator of heel 10 lifts and rands therein, and causes them to be alined when pressed down into the cavity by the presser.

A plate 25 is detachably secured upon the flanges 19 at that side of the mold which 15 conforms to the breast of the heel, and the edge 26 of such plate forms the breast edge of the entrance to the mold. Said edge 26 is made sufficiently sharp to cut leather, and other rand material, in cooperation with a 20 cutting edge on the presser, as presently described, whereby to trim off the ends of the rand strip flush with the breast of the heel being made. The plate 25 is therefore a shear blade.

25 I have also provided, below and in extension of the mold, a chute formed by bars 27—27 and 28—28, into which the heels pass from the mold and in which they are frictionally supported and remain while the adhesive used for coating the lifts is drying. The bars forming such chute are formed, arranged, supported and adjusted substantially as described in my aforesaid Patent 30 No. 1,534,313 and, as the present invention 35 involves no novelty in this part of the machine, but any character of chute may be here used, description in detail of this part of the machine is unnecessary. It is sufficient for the purposes of my present invention 40 that collections of lifts and rands are assembled in a mold and are forced through the mold by pressure applied from time to time on the topmost one of the constantly augmented pile of heels, and that the heels 45 are confined and supported under pressure in such mold, or in an extension chute, for a long enough time to become so firmly joined together that they may be afterwards handled as units.

50 In the rear part of the column 16 is a guideway 29—29, in which is mounted a slide or head 30, (Figs. 1, 3 and 4), carrying a presser 31.

Said presser is shown in detail in Fig. 10. 55 It depends from a bracket 32 which projects from the forward side of the sliding head and includes a plate 33 overlying the top of the sliding head and secured thereto, such plate being a means for detachably connecting the bracket to the head. The presser 31 conforms in outline approximately to the mold cavity and on its breast end carries a shear blade 34 complementary to the blade 25. The blade 34 is fitted into a recess in the 60 breast side of the presser, wherein it is posi-

tioned by a pin 35, (preferably made as a screw), and it is further and more rigidly held by a clamp plate 36 attached to the side of the presser block by a screw 37 (passing through a hole 38 in the clamp plate and into a tapped hole 39 in the presser block), which plate has a lip 390 arranged to press against the shear blade, and a notch 40, to receive the pin 35.

I have provided means for insuring accurate matching and co-action of the shear blades 25 and 34. For this purpose the bar 21, which lies across the front of the mold, carries screws 41 which are adapted to crowd the mold against the rear side of the cavity in the table in which it is received, thus locating the blade 25 immovably in a definite position. And the presser is adjustable in a front to rear direction on the bracket 32, having a rib 42 (Fig. 10), 75 which is confined in a groove 43 in the bracket (Fig. 9), while a clamping screw 44 passes through a slot 45 in the bracket and into a tapped hole 46 in the presser block.

The presser carrying head 30 has a wrist pin 47, by which it is coupled to a connecting rod 48, and the connecting rod is also coupled, by means of a strap 49, with an eccentric or crank pin 50 on a shaft 51, 90 mounted in suitable bearings in the lower part of the column. A worm wheel 52 on one end of the shaft imparts rotation thereto, being driven by a worm 53 on a counter shaft 54, which rotates in bearings suitably 95 arranged on the side of the column 16 and on the top of a post 55, which rises from the base. The shaft 54 is driven by a belt pulley 56 by means of a clutch and under control of a stopping and starting mechanism later described.

The mechanism just described moves the presser up and down in line with the mold cavity and with a range of movement wide enough to cause it to enter the mouth of such cavity, carrying its shear blade 34 slightly past the edge 26 of the complementary shear plate 25, when in its lowermost position, and to raise it so far clear of the mold that the operator may assemble 115 the lifts therein without interference. The guideway 29—29 of course determines the path in which the presser thus moves, and such guideway is preferably parallel with the passageway through the mold and chute. 120 However, it is not essential that these members should be exactly, or even approximately, parallel provided only the presser moves nearly enough in the same general direction as the mold passage to force the 125 assembled collections of heel lifts therethrough, and that it travels in a path which will effect cooperation between the shear blades 25 and 34.

The machine is started by the operator 130

and is automatically stopped after making one cycle. The pulley 56 is loose on the shaft, and cooperates with a clutch cone 57 fast on the shaft, a spring 58 (Fig. 2) 5 constantly tending to withdraw the pulley from the cone. An operating lever 59, preferably terminating in a treadle convenient to the operator's foot, is secured to a shaft 60 having bearings in a post 61 rising from the base. There is secured to the rock shaft 60 in line with the shaft 54 an eccentrically arranged sleeve 62, in which there is an adjustable threaded rod or bolt 63 arranged to bear against a stud 64 projecting from the center of the pulley. Arm 59 and rod 63 thus form a bell crank lever adapted to force the pulley into contact with the clutch cone when the treadle is depressed. A cam 65 is also secured to the rock shaft 60 and 10 bears on a pivoted rock arm 66 connected with a brake lever 67 by a connecting rod 68. The brake lever is provided with a friction pad 69 arranged to bear on the face of the clutch cone, and is pressed toward the cone by a spring 70 confined in a guide 71 on the post 55, which spring acts through a plunger 72 and reacts against an adjustable abutment 73, which is screwed into the guide 71. The connecting rod 68 15 is made in two parts, one of which parts is a pin or stud 74 threaded into the rock arm 66 and consequently adjustable to insure separation of the brake pad or shoe from the clutch cone when the treadle is depressed. When the treadle is released, a spring 75, connected and arranged preferably as clearly shown in Fig. 1, raises the control arm and allows the pulley to be withdrawn from the clutch cone and 20 the brake to be applied at the same time.

A latch lever, having two arms 76 and 77, is pivoted to a bracket 78 on the column 16, and the lower end of its arm 76 lies beside the control arm 59, while its upper arm 77 is drawn toward the column by a spring 79. Arm 77 is also provided with a cam or wiper surface 80, inclined to the direction in which the sliding head 30 travels, and arranged to be engaged by a 25 projection 81, projecting from the side of the sliding head 30. When the control arm is depressed to clutch the driving pulley to the shaft 54, it is carried below the end of latch arm 76, and then immediately after 30 the presser begins to descend, the receding cam surface 80 allows the latch to slip over the control arm, as shown in Fig. 7. When the presser returns to the upper limit of its travel, the projection 81, forcing the cam surface 80 outwardly, disengages the latch from the control arm and permits the pulley to be unclutched and the brake to be applied to the drive shaft. In principle, the stop and start mechanism just described is equivalent to that disclosed in my aforesaid

Patent No. 1,534,313, and is claimed in said patent. The novelty in the present mechanism is embraced particularly in an improved brake having capacity for adjustment and being more readily accessible. 70

The principal new result accomplished by the invention is the building of heels equipped with rands; and a further important and valuable result consists in trimming the ends of the rand strip flush with the 75 breast of the heel, all in one operation with the building action.

A heel of the sort produced with the aid of this machine is shown in Fig. 12. It is made up of any desired number of lifts ^a 80 and a rand ^b. The lifts may all be whole lifts, or one or more of them may be pieced lifts, and they may be assembled in any desired number, depending on the height of heel to be made. The process of building 85 them is as follows:

A sufficient number of lifts to make a heel of the required height, size and style, are taken from appropriate, conveniently arranged, compartments by the operator, 90 coated with adhesive, and placed in a pile within the flaring mouth of the mold. A strip of rand material is then placed on the topmost lift of the pile. It may be first coated with adhesive, or the adhesive already 95 on the topmost lift may be relied on to bind it to the heel. Such rand strip is a strip of leather, or suitable leather substitute, wedge-shaped in cross section, which is as long as the circuit of the heel, except the breast edge. 100 Preferably the strips used are a little longer than this in order to insure that the ends of the rand will come quite up to the breast of the heel. The rand strip is bent by the operator in being laid on the topmost lift 105 of the heel, and is so placed that both ends project from the breast, substantially as shown in dotted lines in Fig. 12. A separator repellent to adhesive is finally placed over the topmost lift and the rand thereon, 110 and the presser is made to descend. In thus descending, the presser forces the assemblage of lifts, with the rand thereon, into the mold and at the same time trims off the projecting ends of the rand. It also causes heels previously placed in the mold to be moved one 115 step farther down the chute and ejects the lowermost heel from the bottom of the chute.

Successive heels are built up in substantially the same way, and when they emerge 120 from the chute they are sufficiently dry, and their parts are firmly enough secured together to enable each heel to be handled as a unit and fed as such to the heel compressor wherein the heels are compacted under great 125 pressure to a condition enabling them to be applied directly to shoes.

The separators placed upon and between successive heels, as above described, prevent the heels from sticking to the presser and to 130

one another, and enable the individual heels to be separated readily when they emerge from the chute. Such separators may be sheets of paper impregnated with paraffin, 5 or otherwise made repellent or non-adhesive to the paste or cement with which the lifts are coated, or they may be shaped rigid blocks or plates convex on one side in conformity with the depression within the rand, 10 and flat on the other side to match the under side of the next adjacent heel. Such plates or blocks may be of any material sufficiently strong to sustain the pressure applied, and having the quality of not adhering to the 15 adhesive, whether such quality is an inherent characteristic of the material or is imparted by impregnation or coating with suitable substances. While the separator blocks conforming on one side to the concave side of 20 the randed heel may be preferred, from some points of view, they are not essential, for satisfactory results may be obtained in making randed heels with the use of thin and flexible separators such as those made of 25 paraffined paper.

By thus building heels with rands in the first instance, a large saving in the time and cost of producing heels ready for attachment to shoes is effected, for the operation of 30 applying and fitting a rand to an already built heel blank, or to a compressed heel, is avoided; while the step of applying a rand to the heel blank, and trimming the rand in the course of building a heel, according to 35 this invention, involves substantially the same, and no more, time and care on the part of the operator as the placing of a lift in the mold, and is a much less particular and less expensive step than that of fitting a 40 rand to a previously built heel.

In this specification and in the following claims, the term "mold" is to be understood as including generically any space having limiting bounds within which heel lifts, or 45 the like, and rands may be placed and confined, in substantial accordance with the principles of this invention.

What I claim and desire to secure by Letters Patent is:

50 1. A heel building machine comprising a mold having the outline of a heel; a shear blade bounding the mouth of said mold at the breast side thereof, and a presser formed to enter said mouth and having a cutting edge complementary to and cooperative with said shear blade.

2. A heel building machine comprising a mold adapted to embrace and make frictional contact with the edges of heel lifts, 60 said mold having at its mouth a cutting edge, and a presser constructed, arranged and operable to force assemblages of heel parts into said mold, and having an edge complementary to the aforesaid edge and 65 adapted to cooperate therewith as a shear.

3. A heel building machine having a mold open at one end for the reception of heel lifts in shape and dimensions conforming to the heels to be built, and having a cutting edge at that side which corresponds to 70 the breast of the heel, and a presser adapted to enter said mold and bear on the heel lifts therein and having a shearing edge complementary to the first named edge.

4. A heel building machine comprising a 75 supporting structure, a mold mounted on said supporting structure and having a through passageway with the outline and dimensions of a heel, a head mounted to reciprocate on said supporting structure in 80 the same general direction as said passageway, and a presser carried by said head and overhanging said mold, said presser being made with a form and dimensions enabling it to enter said mold, the mouth of said 85 mold and said presser having complementary shearing edges and being relatively adjustable transversely to the line of movement of the presser.

5. A heel building machine comprising a 90 supporting structure, a heel receiving mold mounted on said structure and having a through passageway, a shear blade forming one side of the mouth of said mold, a reciprocating head guided on said supporting structure and having a bracket overhanging said mold, a presser depending from 95 said bracket adapted to enter the mold and formed with a cutting edge complementary to said shear blade, and means connecting 100 said presser to said bracket constructed with provisions for adjusting the presser transversely of said cutting edge into correct shearing relation therewith.

6. In a heel building machine of the 105 character described, a heel receiving mold having a shearing edge at the breast side of its mouth and having flaring walls at other sides of its mouth, and a presser complementary to said mold and having a shear 110 blade at its breast side complementary to the first named shear blade.

7. In a heel building machine of the character described, a movable head having a lateral bracket or arm, a heel presser depending from said arm, said arm and presser having provisions for adjustment laterally, and the presser having a shearing edge extending in a direction transverse to the direction of said adjustment.

8. In a heel building machine of the character described, a presser, and a blade detachably fitted to said presser and forming part of the pressing surface thereof, its outer edge being a shearing edge providing a 120 part of the outline of the presser.

9. In a heel building machine of the character described, a presser, a blade detachably fitted to said presser and having a shearing edge providing a part of the out- 125

line of the presser, a pin positioning said blade, and a clamp secured to the presser and overlapping said blade.

10. In a heel building machine of the character described, a mold having a cavity to receive heels, beveled members applied to the receiving end of said mold and forming a flaring mouth thereto, and a shear blade arranged to form a part of the bounding

10 edge of said mouth.

11. In a heel building machine of the character described, semi-tubular members fitted to one another to form collectively a mold having a heel receiving passageway, 15 said members having complementary keyways, and an aligning key fitting said keyways.

12. In a heel building machine of the character described, a table having an opening, a mold having a passage to receive heels 20 adapted to enter said opening and having a flange adapted to rest on said table, and means connected with said table adapted to exert pressure on one side of said mold for locating and securing the mold in a given 25 position.

13. In a heel building machine of the character described, a supporting frame, a mold having a heel receiving passage, a sliding head mounted and guided on said 30 frame to move reciprocatively in a fixed path extending in the same general direction as said passage, and a presser carried by said head overhanging the entrance to said passage and being formed and arranged to

enter said passage upon movement of the head in one direction.

14. In a heel building machine of the character described, a supporting frame, a mold having a heel receiving passage, a sliding head mounted and guided on said frame to move reciprocatively in a fixed path extending in the same general direction as said passage, a presser carried by said head overhanging the entrance to said passage and being formed and arranged to 40 enter said passage upon movement of the head in one direction, said mold at the entrance to its passage and the presser having complementary shearing cutters.

15. In a heel building machine of the character described, a supporting frame, a mold having a heel receiving passage, a sliding head mounted and guided on said frame to move reciprocatively in a fixed path extending in the same general direction as said 55 passage, a presser carried by said head overhanging the entrance to said passage and being formed and arranged to enter said passage upon movement of the head in one direction, said mold at the entrance to its 60 passage and the presser having complementary shearing cutters, and being relatively adjustable transversely to the direction of movement of the sliding head so as to place 65 said cutters in shearing relationship.

In testimony whereof I have affixed my signature.

EDWIN HANSALPAKAR.
